APPARATUS FOR HOISTING ANCHORS AND
MOORING VESSELS

James H. Lucas, Seattle, Wash.

Application December 26, 1934, Serial No. 759,190

3 Claims. (Cl. 254—184)

This invention relates to an apparatus for hoisting anchors and for warping and mooring vessels.

Where small crafts, and particularly pleasure yachts are operated by a crew of few persons, considerable difficulty is frequently encountered, in the raising of anchors, particularly when in deep water with a long heavy chain. Additional difficulty is met in warping such vessels to wharves or landings, against adverse winds and tides.

An object of my invention, therefore, is to provide a small and compact apparatus, with relatively few parts, and easily and cheaply constructed, whereby a heavy anchor may be easily hoisted from deep water by one individual, and whereby such vessel may be easily warped to a desired landing by one person against wind and tide.

20 A further object is to provide a compact apparatus with its machined movable parts mounted in a housing, wherein lubricating oils may be held in contact with bearings, and the finished parts protected from contact with salt water spray. Also to provide both manual and mechanical means for operating the gears, with means for controlling the movements of the gears, and for adjusting the position of gears in suitable alignment with others; with further means for 25 mooring the craft.

30 A still further and particular object is to provide a simple apparatus, which may be easily operated, and which will provide a high degree of lifting power, for rapidly hoisting an anchor and chain from deep water.

35 With these and other objects as will appear in the specification, I have illustrated my invention by the accompanying drawing, of which:

Figure 1 is a top plan,

40 Figure 2 is a section view taken on lines 2—2 of Figure 1.

Figure 3 is an end elevation taken on lines 3—3 of Figure 1, with parts broken away and parts removed,

45 Figure 4 is a detail top plan of the eccentric plate and lower stub shaft in section.

Like numerals on the different figures represent like parts.

50 5 represents the base or bottom between the frame end plates 6 and 7 of the housing 8. This may be bolted or otherwise attached to the forward part of the deck 8' of a vessel.

55 9 represents the main shaft which is rotatably mounted through frame plates 6 and 7. Each end of the shaft protrudes slightly beyond each

respective plate. Between the plates and near one thereof a circular block 10 is affixed to the shaft. On the inner face of this block is affixed a toothed ring, or crown gear 11. Driving pinions 12 and 12' are held in meshed connection with the gear, on the ends of the stub shafts 13 and 14.

Cable holding bitts 15 are affixed to and protrude angularly from the upper portion of the housing, and are suitably spaced apart to provide 10 bitt posts around and between which a mooring cable may be looped or woven in the usual manner, for holding vessels to wharves or other mooring stations.

The bitts are tubular and so provide supports 15 and bearing guides for the stub shaft 13. This shaft may be mounted alternately in either of the bitts, as may be desired for right or left hand actuating power therefrom upon the pinion 12. The outer end of shaft 13' protrudes beyond the top of the bitts to provide means for connecting any simple turning means, as a removable hand crank.

The auxiliary shaft 14 is projected perpendicularly through the floor of the housing and may 25 be carried down through the boat deck to any desired point for convenient operation, particularly in stormy weather, either manually by means of a crank handle 17, or by any belt mechanically driven around pulley 18.

30 This shaft 14 is rotatably mounted through a journal sleeve 19 which is eccentrically affixed relative to the center of an adjustable plate 20. Slots 21 in the rim of this plate, for holding bolts, permit the plate to be turned sufficiently to 35 change the position of the pinion teeth in the gear. The eccentric mounting provides for slight contact between such teeth, when the auxiliary shaft is not required for power, and also provides for adjustment of the pinion after wear 40 may have created excess looseness. An ordinary thrust bearing washer 16 is placed around shaft 9 in front of block 10.

45 On one end of the main shaft 9, is affixed a sheave wheel A, commonly known as a "wild cat", for hoisting an anchor chain or cable; and on this wheel adjacent the end 6 is a circular ratchet shoulder 22, over which rides a pawl 23 on pivot 24. The pawl may be lifted from the ratchet to permit free turning of the wheel in either direction, but when in lowered position it prevents the wheel from turning backward when an anchor is being hoisted.

50 A suitable opening 25 through the base plate permits the supply of chain cable in the locker 55

beneath, to be drawn out over the sheave wheel when the anchor is launched.

The free movement and speed of the wheel is easily controlled by a foot brake and pedal 26, 5 and lever 27, which latter is attached at its inner end to a pin 28, pivotally mounted through the plate 6. The inner end of the pin actuates an ordinary toggle lever 29 attached to one end of an ordinary resilient brake band 30. The other 10 end of the band is attached to a fixed pin 31. A brake drum 19' or face is provided around the block 10 between the plate 6 and the gear 11.

A spring 32 normally holds the band in free 15 position over the drum, but is easily overcome by pressure on the pedal.

On the end of the shaft 9 opposite wheel A, is 20 affixed a spool drum B, commonly known as a "gipsy" for winding a rope or mooring cable, thereon. When necessary to warp the vessel toward a wharf or against wind or tide, one end of the cable is attached to some fixed object as on 25 the wharf, and the other end or bight of the cable is made fast to the drum, and the latter revolved till the cable winding around the drum draws the vessel in the direction desired.

The same cable may be then detached from the drum and made fast around the bitts for retaining the vessel in such moored location.

Having described my invention, I now claim 30 as new:

1. An apparatus for hoisting and controlling the lowering of boat anchors, comprising a housing with a shaft revolvably mounted therethrough, a sheave wheel for hoisting a chain mounted on one end of the shaft and a winding drum for reeling a warping cable mounted on the other end of said shaft, a ratchet wheel mounted 35 on the sheave wheel and a pawl for controlling the movement of the shaft in one direction, a toothed ring gear fixedly mounted to the shaft in the housing for operating the same, a relatively smaller driving pinion mounted in mesh with the gear, a stub shaft revolvably mounted through the upper portion of the housing with the inner end thereof affixed in the pinion and the outer end 40 adapted to be turned for driving the pinion and gear wheel for revolving the sheave wheel and

winding drum, a pair of tubular bitts affixed to and projecting above the housing in spaced relation with each other adapted for weaving a mooring cable thereover, and the interior of the bitts adapted to provide supporting sleeves for 5 said stub shaft projected through one of said bitts, a brake drum mounted in the housing affixed to the ring gear, with a brake band adjustably mounted around the brake drum, and means outside the housing for tightening and releasing 10 the band, to control the lowering of the anchor.

2. An apparatus for hoisting anchors for vessels, comprising a housing with a shaft revolvably mounted therethrough, a sheave wheel mounted on one end of the shaft for raising an anchor cable, a ring gear attached to the shaft within the housing, and a driving pinion in mesh with the gear, and affixed to the top end of a stub shaft for driving the pinion, the stub shaft projected downward through a rotatable plate connected to the base of the housing, the journal bearing for the stub shaft eccentrically disposed through the plate relative to the center of said plate, for adjusting the position of the pinion teeth in connection with the gear from a point below the housing, the lower end of the stub shaft designed to extend downward through the deck of the vessel and provided with means for driving the stub shaft manually and mechanically, for turning the 20 sheave wheel and hoisting an anchor.

3. An apparatus for hoisting and lowering an anchor of a vessel and for mooring the same, comprising a housing, with a ring gear therein mounted on a shaft with a sheave wheel on one end 35 thereof, a pinion gear in mesh with said ring gear, and driven by a stub shaft projected through the housing, a pair of tubular bitts projecting above said housing in spaced relation with each other and adapted for weaving thereover and between the same a mooring cable to hold the vessel to a wharf, the interiors of said bitts adapted for supporting said stub shaft in revolvable connection therein for revolving said 40 gears for hoisting an anchor chain over said sheave wheel.

JAMES H. LUCAS.
